FIG. 1

FIG. 2

FIG. 3

FIG. 4

FIG. 5

FIG. 6

FIG. 7**FIG. 8**FIG. 1 is a perspective view of an adjustable lighting fixture showing our new design,

FIG. 2 is a top view thereof,

FIG. 3 is a bottom view thereof,

FIG. 4 is a side view thereof,

FIG. 5 is an enlarged view of the portion of the face thereof, which is designated 5—5 in FIG. 4,

FIG. 6 is an end view thereof, and

FIGS 7, 8 and 9 are end views of the adjustable lighting fixture in alternate positions.

The faceting shown in FIG. 5 is omitted in FIGS. 1, 2, 4, 6, 7, 8 and 9 for convenience of illustration, it being understood that the faceting is uniformly continuous over the face of the fixture.

We claim:

The ornamental design for an adjustable lighting fixture, substantially as shown and described.
